UNITED STATES PATENT OFFICE.

WARREN B. MARTINDALE, OF KENOSHA, WISCONSIN, AND ERNST REINHOLD MALMBORG, OF ST. LOUIS, MISSOURI, ASSIGNEES, BY DIRECT AND MESNE ASSIGNMENTS, TO THE ELECTRIC DATE AND TIME STAMP COMPANY, OF ILLINOIS.

ELECTRIC TIME-STAMP.

SPECIFICATION forming part of Letters Patent No. 449,081, dated March 24, 1891.

Application filed August 22, 1889. Serial No. 321,685. (No model.)

To all whom it may concern:

Be it known that we, WARREN B. MARTINDALE, of the city and county of Kenosha, and State of Wisconsin, and ERNST REINHOLD MALMBORG, of St. Louis, Missouri, have invented certain new and useful Improvements in Electric Chronometric Hand-Stamps; and we do hereby declare that the following is a full and exact description thereof, reference being had to the accompanying drawings, and to the letters and figures of reference marked thereon, making a part of this specification.

Our invention relates to automatic electrically-operated time printing-stamps of that class by which an impression is made upon the upper surface of the paper to be stamped.

It has for its object to simplify the construction of such stamps and to render the same more compact, more accurate, less liable to get out of repair, and more convenient for use.

It consists in the novel combination and arrangement of parts constituting the improved stamp, as hereinafter described and claimed.

In the accompanying drawings, Figure 1 is a central longitudinal vertical section of our improved time-stamp in line $x x$ of Fig. 2, the pawl-springs being omitted. Fig. 2 is a transverse vertical section, on an enlarged scale, in line $y y$ of Fig. 1. Figs. 3, 4, and 5 illustrate, respectively, different positions of the pawl and dog which lock and release one of the type-wheels. Fig. 6 is a detail bottom view on same scale as Fig. 2, partly in elevation and partly in section in the plane of the wheel-shaft, illustrating the arrangement of the type-wheels, ratchets, regulating-disks, and pawls; Fig. 7, a transverse section in detail in line $z z$ of Fig. 1, and Fig. 8 is a detail top view of the armature and its pivotal supporting-arm.

Similar letters and numerals refer to like parts in all the figures.

A represents the base-plate of the stamp; B, the arm carrying the printing mechanism, said arm being hinged to one end of the base-plate; C, the case carrying the printing mechanism, and which is rigidly secured to the outer end of the hinged arm B, and D an elec-

tro-magnet in horseshoe form, whose two parallel soft-iron arms are curved in a segmental form, in order to occupy the least possible amount of space in proportion to its size and the power exerted thereby. The cross-bar E of this horseshoe-magnet is preferably secured to the bottom of the case C at the inner end thereof, so that the arms of the magnet project upward and forward therefrom in a quadrant curve having the axial shaft F of the printing-wheels as its center, whereby the wheels are overarched concentrically by the magnet.

The armature G for the magnet is constructed with a central arm G', extending at a right angle therewith from the middle of its upper edge. The outer end of said arm is forked to embrace a spring, and is pivoted to the rear or inner end of the casing above the magnet between two lugs $a a$, as shown in Figs. 1 and 8, so that the arm is made to extend longitudinally over the magnet. A spring m , coiled about the pivot-pin between the forked ends of the arm, is made to bear against it to lift and hold it up. The armature is thereby hinged to oscillate in a plane transversely to the axes of the arms of the magnet, and its front portion is made to depend above and in front of and in close proximity to the poles of the magnet in such form as that when attracted by the magnet it will swing down in front of the ends of the arms thereof transversely to the length of the same. Since some portion of the armature is thus constantly in close proximity to the ends of the core of the magnet, the advantage of the stronger attraction which is exerted by the magnet near its poles is utilized during the entire movement of the armature, whereby increased power is exerted and greater length of motion of the armature is secured from a given amount of battery-power.

The date and time registering wheels 10, 11, 12, 13, 14, 15, 16, and 17 are all mounted to revolve on the one axial shaft F, which is secured in the lower portion of the case C under the magnet D and transversely thereto, as hereinbefore described. The two outer registering-wheels 10 and 17 turn independently

upon the shaft F. They are held in position by suitable movable catches projecting from the case C, and are adjusted, as required, by hand. Of said wheels the one 17 on the left is designed to print the month and the other 5 10 on the right the year.

The minutes are indicated and printed by means of the two wheels 11 and 12, revolving freely side by side. The periphery of the 10 first or units wheel 11 is divided into ten spaces bearing, respectively, the nine digits and cipher. The second or tens minute-wheel 12 is divided into twelve peripheral spaces bearing, respectively, the figures 1 to 5 and a cipher 15 in two series.

The remaining type-wheels are arranged in the order of their moving, as follows: The hour-wheel 13, (see Fig. 3,) divided into twelve peripheral spaces and bearing thereon, respectively, the numbers 1 to 12 and a punctuating-dash, is mounted next to the second or tens minute-wheel 12. The meridian-wheel 14, divided into twelve peripheral spaces and bearing thereon the letters "A.M." and "P.M." 20 alternately, is mounted next to the hour-wheel. The two date-wheels 15 and 16, for printing the days of the month, are mounted next to the meridian-wheel 14. The first date-wheel 15 is divided into ten peripheral 25 spaces bearing thereon the nine digits and cipher, and is a duplicate of the units minute-wheel 11. The second date-wheel 16 is divided into twelve peripheral spaces bearing the numbers 1 2 3 in three series, with blank 30 spaces between each. The first or unit wheel 11 carries upon its hub, to revolve with it on the right, first, a disk b, having a single peripheral notch, and, second, a ratchet-wheel c, of the same diameter, having ten teeth. 35 The second or tens minute-wheel 12 carries upon its hub, to revolve with it on the left, first, a ratchet-wheel d, having twelve teeth, and, second, a disk e, of the same diameter, having two peripheral notches. The hour-wheel 13 carries upon its hub to the left a ratchet-wheel f, having twelve teeth, and a disk g, of the same diameter, having a single 40 peripheral notch. The meridian-wheel 14 carries upon its left and secured to its hub, to 45 revolve with it, a ratchet h, having twelve teeth, and a disk i, of like diameter, having six peripheral notches. The first date-wheel 15 carries upon its right, secured to its hub, to 50 revolve with it, a disk having a single peripheral notch and a ratchet k, of like diameter, having ten teeth, and the second date-wheel 16 carries upon its left, secured to its hub, a ratchet l, having twelve teeth.

The several registering-wheels are actuated 55 60 by a series of pawls K K', &c., pivoted at their upper ends to the armature G, so as to oscillate with it. These pawls severally depend each in position to engage one of the ratchet-wheels, so that the upward movement 65 of the armature under the stress of its spring m shall cause the wheels to revolve, the engagement of each pawl with its ratchet being

enforced by a spring 35, interposed between it and the front of the case, as shown in Fig. 1. The lower end of the first pawl K is bent in form 70 to engage the ratchet C, attached to and revolving with the disk b and first minute-wheel 11. The lower end of the second pawl K' is forked to span the minute-wheels 11 and 12, and its two fingers are adapted the one to engage the 75 ratchet d of the second minute-wheel 12 and the other to rest upon the periphery of the disk b of the minute-wheel 11, so that the second finger, being upheld by the disk, will operate thereby to hold the first finger out of 80 engagement with said ratchet d until the one notch on the disk b is brought into register with the second finger, and by allowing it then to swing inward will permit an engagement of the first finger with the ratchet d, so 85 as to produce a rotation of the second wheel 12. The free end of the third pawl from the right K² is likewise forked to span the hour-wheel 13 and form two fingers, one of which is adapted to engage the ratchet f of the hour-wheel and the other to ride on the disk e, revolving with the second minute-wheel 12, so as to prevent an engagement of the first finger with its ratchet until the second finger 90 swings into one of the two notches on the disk 95 e. The hour-wheel 13 is thus moved twice during each revolution of the second minute-wheel 12. The fourth pawl K³ is also constructed with a forked end to span the meridian-wheel 14, and the first of its two fingers 100 is adapted to engage the ratchet attached to said meridian-wheel and the other to ride on the disk g, revolving with the hour-wheel 13, whereby the pawl is permitted to swing into engagement with the ratchet of the meridian-wheel and move the same one step only at each revolution of the hour-wheel 13. The fifth pawl K⁴ rides upon the periphery of the disk i, revolving with the meridian-wheel 14, and it is made wide enough to overlap the ratchet k, attached to the first date-wheel 15. By swinging at every other step of the meridian-wheel into a notch in the disk i the pawl is permitted to engage the ratchet k, and thereby move the wheel 15 one step. The 110 sixth pawl K⁵, which is the last on the left, is forked to span the two date-wheels 15 16, so that one of its two fingers may ride on the disk k of the first date-wheel 15 and the other engage the ratchet l of the second date-wheel 16, when the first finger swings into the notch in said disk, and thereby move the second date-wheel one step at each revolution of the first.

The pawl K², actuating the hour-wheel, is 115 prevented from dropping into engagement with its ratchet until the pawl K' drops into engagement with the ratchet of the second minute-wheel to move it, and the movement of the hour-wheel is made to be in all cases 120 synchronous with that of the minute-wheel by means of a pin n, which is fitted to the pawl K' of the minute-wheel to project therefrom laterally in front of the pawl K² of the 125

hour-wheel, so as to operate to hold said pawl K² until the pawl K' drops into engagement with its ratchet. In like manner the engagement of each of the pawls K³, K⁴, and K⁵ with its appropriate ratchet is controlled so that it shall be synchronous with that of the pawl next preceding it by means of a similar pin n, projecting laterally from the first pawl, in order in front of that next succeeding it, as illustrated in Fig. 6 of the drawings.

Each date and time registering wheel is positively locked as soon as its movement is completed, and is so held until the proper moment for its next move by means of a spring-actuated dog 17, pivoted upon a rod J, extending across the front of the case, and made to engage the ratchet of the wheel, its engagement being automatically enforced by means of a suitable spring 36. (See Fig. 1.) Each dog 17 is formed with a tooth adapted to enter the notches in its appropriate ratchet-wheel, and is preferably provided with a curved arm r (see Figs. 1 to 5) to extend upwardly from its pivoted end alongside of the proximate pawl-lever K K', &c., actuating the same ratchet-wheel. This curved arm r is provided with a lug or pin t, formed laterally on the upper end thereof in position to engage with a similar lug u on the side of the pawl-lever, so that when the pawl swings into engagement with the ratchet the lugs t u are brought into contact, and the dog 17 is by the first movement of the pawl lifted out of engagement with the ratchet, which is thereby permitted to move. When the lugs t u have passed each other, the dog 17 again drops into engagement with the ratchet. The lugs t u are so placed as that the lug u on the pawl-lever passes outside of and free from the lug t on the dog, as shown in Fig. 3, except when the pawl swings into engagement with the ratchet. The lug u on the pawl will then pass on the inner side of the lug t on the dog, as shown in Fig. 5, and move it outward, lifting the dog from the ratchet, as above described.

To prevent the jar incident to taking an impression from the stamp from causing the armature to drop down independently of the attraction of the magnet, we provide a small spring-actuated stop 18, pivoted at its lower end to the magnet at the lower side of its front end, and which automatically swings outward therefrom to bring its upper end under the armature. This stop has small arms 38 38 (see Fig. 2) projecting therefrom laterally on either side over the face of the magnet, which operate as an armature to draw the stop toward the magnet out of the way of the armature G when the magnet is energized by the current.

The movement of the stamping-arm B to produce an impression is facilitated by means of a knob 19, fitted centrally upon the top of the stamping-case C. This knob 19 is preferably mounted upon a separate shank or stem 20, fitted to the case, the knob being recessed to embrace the upper end of the shank

loosely and have free play thereon, and confined by means of a central pin 21, which is made to pass down centrally through the shank, and is held by a wide-headed screw 22 entering its outer end. A spiral spring 23, interposed between the knob 19 and shank 20, is fitted within a central recess in the shank to encircle the pin. This spring serves to carry and hold the knob 19 in its outer position.

A latch or catch 24 is pivoted to the under side of the top of the case C, immediately over the arm G' of the armature and in front of the lower end of the knob-pin 21. The lower end of the catch depends through a slot in the arm of the armature G'. From its upper end, at its pivotal connection, an arm extends back under the end of the knob-pin 21, and is slotted to receive it, so that the head of the screw 22 upon said end shall overlap the edges of the slot, whereby when the knob 19 is upheld in its normal position by the stress of the spring 23 the arm of the catch 24 is drawn up, and the catch thereby held in its normal position, with its lower end depending through the arm G' of the armature. When the knob 19 is depressed, as when it receives the necessary pressure or blow to produce an impression from the registering-wheels, the downward movement of the pin 21 operates to free the arm of the catch 24, so that it may be automatically swung downward by the action of a spring 25, engaging its outer end. As the arm swings downward it will cause the catch 24 to swing forward so as to project over the top of the arm G' so soon as the armature is depressed. A return upward movement of the armature, operating to move the registering-wheels, is thus prevented until the knob 19 has returned to its normal position. The upward movement of the knob will draw the catch 24 back to its first position, and so permit the armature to rise. The spring 25, by which the catch 24 is actuated, will permit the catch to yield and allow the armature to be carried down at any time independently thereof, when attracted by the magnet, even though the knob 19 be at the moment depressed, and the upward movement of the armature is prevented by the catch only at the moment an impression is being taken and the knob is being forced down for the purpose.

The electrical connection of the wires from the battery and time transmitting mechanism in circuit with the magnet is effected by means of two binding-posts 26, 27, (see Fig. 7,) one of which 26 is secured to the hinge-pin 40 of the stamping-arm B in the base A and through said arm with one end of the coil of the magnet, and the other 27, insulated from the frame A, is connected with an insulated pin 28, made to contact with the end of an insulated conducting-strip 29, (see Fig. 7,) which is fitted in a recess 41 under the stamping-arm B (see Fig. 1) and connected with the opposite end of the coil of the magnet. The

insulation of the strip 41 may be effected, as shown in Fig. 1, by means of insulating-blocks 45 45.

- The printing-wheels are preferably inked by means of an inking ribbon 42, carried upon two spools 30 31 (see Fig. 2) and led in the customary manner from the one to the other, over the type on the wheels at line of print; but any form of inking device may be used.
- 10 In the operation of the device the outer printing-wheels 10 and 17 are adjusted by hand, the one 10 to register the current year and the other 17 to register the current month. The conducting-wires 43 43 from a suitable battery in a circuit which is closed at regular intervals in the customary manner by means of a clock are connected to the binding-posts 26 27, and the electro-magnet D is thereby included in the circuit, so that the magnet will become energized each time the circuit is closed. So soon as the magnet is thus energized it will attract and depress the armature G. The armature when thus depressed will carry down with it the several pawls K' K² K³, &c., so that each of them will be in position to make a new engagement with its appropriate ratchet, and will when the pawl rises with the upward movement of the armature cause the wheel which it engages to 30 turn one step. The upward movement of the armature and its pawls is produced so soon as the electric circuit is opened by the stress of the coiled spring m, which actuates the arm G' of the armature. With the circuit closing 35 at each minute the first minute-wheel 11 will be moved one step at each minute, thereby bringing the digits in succession to line of print, and so soon as the number "9" has been printed the notch on the adjacent disk b will 40 permit the pawl of the second minute-wheel 12 to swing into engagement with its ratchet to bring the next unit in order thereon to line of print to form with the first wheel 11 the numerals of two places needed to indicate the 45 minutes above nine. At the next move after the number "59" is reached the ciphers on both wheels will be brought to line of print, and a notch on the disk e of the tens minute-wheel will allow the pawl actuating the hour-wheel 50 to drop into engagement therewith to produce simultaneously its movement to change the hour. In like manner the meridian-wheel will be moved at the end of every twelve hours, the first date-wheel at the end of every 55 twenty-four hours, and the second date-wheel at the end of every complete revolution of the first to produce the double numbers indicating the days of the month.

An impression may be obtained from the 60 wheels at any moment upon paper placed upon the pad 32 under the registering-wheels by pressing down the hinged stamping-arm B and with it the case C, carrying the wheels and inked ribbon, the movement being obtained by pressure or a blow upon the knob

19, while the retraction of the stamp mechanism is produced by the action of the spring 33 in the base of the stamp.

The automatic movement of the printing-wheels under the action of the magnet at the moment an impression is being taken from the wheels is prevented by the lost motion allowed to the knob 19, which by actuating the latch 24 locks in manner as described the armature G so long as the requisite pressure is maintained upon the knob to produce the impression, the latch being thereafter automatically released by the action of the spring 23 raising the pin 21.

We claim as our invention—

80

1. The combination, with the case of a time-stamp and the indicating mechanism therein, of an electro-magnet having a segmental form secured at one end to the lower plate of the case, an arm pivoted to the case above the magnet to extend in a direction parallel with its length above its upper or convex side to and beyond its upper end, and an armature carried by said arm to oscillate in a direction at right angles to the core of the magnet and 90 actuate the indicating mechanism, substantially in the manner and for the purpose herein set forth.

2. The combination, with the case of a time-stamp and with a series of time-wheels revolving upon a common axis in said case, of an electro-magnet fixed in the case and bent in a segmental form, having the axis of said wheels as its center, an armature oscillating in a direction at a right angle with the core 100 of the magnet, an arm carrying said armature and extending from the front of the magnet above it in a direction parallel with the length thereof to a pivotal point at the rear of the head, and pawls coupled to said armature and 105 engaging said time-wheels to actuate them by the movement of the armature, substantially in the manner and for the purpose herein set forth.

3. The combination, in an electrical time-stamp, of the base-plate, the hinged arm, the case carried by said arm, the electro-magnet inclosed in said case, the train of registering-wheels actuated by the movements of the armature of the magnet, and the binding-posts electrically connected mediate with the coil of the magnet, the one through the arm of the stamp and the other through a conductor insulated from the stamp and its base, substantially in the manner and for the 110 purpose herein set forth.

4. The combination, in an electrical time-stamp, of its electro-magnet, the armature moved thereby, the train of registering-wheels actuated by the movements of said armature, 115 the spring-supported stamping-arm carrying said wheels and electro-mechanical devices, a yielding spring-seated knob mounted in the end of the stamping-arm, and a spring-actuated catch normally retracted and held out 120

125

130

135

of engagement with the armature of the magnet by said knob, substantially in the manner and for the purpose herein set forth.

5. The combination, with an electro-magnet, an armature actuated thereby, and the time indicating and registering mechanism operated by the movement of said armature, substantially as herein described, of a second armature in position to be actuated by the
10 magnet and when normally at rest to lock and prevent a movement of the first armature,

substantially in the manner and for the purpose herein set forth.

In testimony whereof we have signed our names to this specification in the presence of 15 two subscribing witnesses.
